UNITED STATES PATENT OFFICE.

LOUIS E. KRAFT, OF FORT WAYNE, INDIANA, ASSIGNOR TO FORT WAYNE TIRE & RUBBER MANUFACTURING COMPANY, OF FORT WAYNE, INDIANA, A CORPORATION OF DELAWARE.

DESIGN FOR A PNEUMATIC-TIRE TREAD.

55,057.

Specification for Design.

Patented May 4, 1920.

Application filed November 26, 1919. Serial No. 340,947. Term of patent 3½ years.

To all whom it may concern:

Be it known that I, LOUIS E. KRAFT, a citizen of the United States, residing at Fort Wayne, Indiana, have invented the new, original, and ornamental Design for a Pneumatic-Tire Tread, of which the following is a specification, reference being had to the accompanying drawing, forming a part thereof.

The figure is a face view of a tread showing my new design, and,

Fig. 2 is a transverse sectional view.

I claim:

The ornamental design for a pneumatic tire tread as shown.

LOUIS E. KRAFT.
